Attorney

UNITED STATES PATENT OFFICE.

THOMAS J. LOWTHER, OF GULFPORT, MISSISSIPPI.

SHEATHING OR CASING FOR HULLS OF WATER-CRAFT.

1,281,182.

Specification of Letters Patent.

Patented Oct. 8, 1918.

Application filed April 22, 1918. Serial No. 230,045.

To all whom it may concern:

Be it known that I, THOMAS J. LOWTHER, a citizen of the United States of America, and resident of Gulfport, in the county of 5 Harrison and State of Mississippi, have invented certain new and useful Improvements in Sheathings or Casings for Hulls of Water-Craft, of which the following is a specification.

10 This invention relates to the preservation of wood and has as its primary object the provision of means for protecting the bottoms of wooden ships against injurious insects or worms and to render the said wooden 15 ships and barges absolutely leak-proof.

Furthermore, an object of this invention is to eliminate danger of wooden ships being water logged to obviate recalking of the same.

20 It has been found in practice that wooden hulls may have their durability increased to a very marked degree by the employment of this invention and wooden hulls and barges that have been impaired and made practically useless by the action of worms have 25 been reclaimed and the cost incident thereto has been minimized and has amounted to no more than the cost of calking and coating the same with copper paint.

30 A still further object of this invention is to produce a ship of the character described which will develop increased speed in proportion to the power applied as compared with ships now in common use, and furthermore, to produce a ship having a minimum 35 tendency to roll in heavy seas.

With the foregoing and other objects in view, the invention consists in the details of construction, and in the arrangement and 40 combination of parts to be hereinafter more fully set forth and claimed.

In describing the invention in detail, reference will be had to the accompanying drawings, forming part of this specification, 45 wherein like characters denote corresponding parts in the several views, and in which—

Figure 1 illustrates a side view of a barge with the sheathing forming the subject matter of the invention applied thereto;

Fig. 2 illustrates an underneath enlarged 50 view of a fragment of a hull;

Fig. 3 illustrates a sectional view of one embodiment of the invention; and

Fig. 4 illustrates a sectional view of another embodiment. 55

In these drawings A denotes a barge, the hull of which is provided with strips of wood B, preferably creosoted or otherwise treated to preserve the texture of the wood, said strips having their edges beveled at the inner 60 sides, as shown at C to form undercuts. The spaces between the strips are filled by a flexible cement which, in its plastic state, enters back of the wooden strips in the recesses formed by the beveled surfaces, thus constituting a strong anchorage for the cement, sufficient in itself, in most instances, to retain it in place, but as a further means for insuring firm anchorage of the cement, the heads D of tacks are embedded in the cement, 65 and the shanks E of the tacks are driven into the sheathing F of the hull A. To increase the speed of the boat and to prevent its rolling, one embodiment of the invention provides for having the surface of the composition or cement concaved transversely, as shown at G, so that the outer surface of the hull presents a series of plain and recessed undulations which, as stated, lend to the stability of the ship and increase its speed proportional to the power applied. 75

In that form of the invention shown in Fig. 4, the wooden strips H have beveled sides I constituting undercuts to form pockets for the anchorage of the cement J and in this 80 form, the cement covers the wooden strips and the outer surface presents a series of alternate convexities and concavities, the object of which has been stated, and in this last mentioned construction, tacks may be employed, if desired, as a further means for anchoring the cementitious coating. 85

I claim—

1. In a sheathing or casing for hulls of water craft, strips of wood having undercuts 90 edges attached to a hull of a craft, and flexible cement deposits between the said strips and extending into the spaces below the

undercuts of the strips, said cement deposits having concaved surfaces.

2. In a sheathing or casing for hulls of water craft, strips of wood having undercut edges attached to a hull of a craft, flexible cement deposits between and over the said

strips and extending into the spaces back of the undercuts of the strips, the surface of the cement deposits having alternate ridges and grooves extending longitudinally of the hull. 10

THOMAS J. LOWTHER.
